STEAM-COOKING CASSEROLE

Helen E. Dumbeck, Eugene, Oreg.

Application February 10, 1958, Serial No. 49,580

Term of patent 14 years

(Cl. D44—1)

FIG. 1

FIG. 2

Figure 1 is a top plan view of a steam-cooking casserole showing my new design; and

Figure 2 is a side elevational view thereof.

The side opposite that shown in Figure 2 is substantially identical thereto.

I claim:

The ornamental design for a steam-cooking casserole, substantially as shown and described.
